UNITED STATES PATENT OFFICE.

SEYMOUR J. STEWART, OF NEW ORLEANS, LOUISIANA.

DESIGN FOR AN ELECTRIC ILLUMINATOR.

43,914.

Specification for Design.

Patented Apr. 22, 1913.

Application filed January 4, 1913. Serial No. 740,225. Term of patent 7 years.

To all whom it may concern:

Be it known that I, SEYMOUR J. STEWART, a citizen of the United States, residing at New Orleans, Louisiana, have invented a new, original, and ornamental Design for an Electric Illuminator, of which the following is a specification, reference being had to the accompanying drawing, forming part hereof.

The figure is a perspective view of an electric illuminator showing my new design.

I claim:

The ornamental design for an electric illuminator, as shown.

SEYMOUR J. STEWART.

Witnesses:

W. R. DOUGLAS, Jr.,
GEO. KELLER.
